ATTORNEY.

UNITED STATES PATENT OFFICE.

FRANCIS J. FARRELLY AND ALFRED GREINER, OF HARTFORD, CONNECTICUT.

CATHODE FOR X-RAY TUBES.

1,275,542.

Specification of Letters Patent. Patented Aug. 13, 1918.

Application filed December 28, 1914. Serial No. 879,263.

To all whom it may concern:

Be it known that we, FRANCIS J. FARRELLY, a citizen of the United States, and resident of Hartford, county of Hartford, 5 and State of Connecticut, and ALFRED GREINER, a subject of the Emperor of Germany, and resident of Hartford, county of Hartford, and State of Connecticut, have invented certain new and useful Improvements in Cathodes for X-Ray Tubes, of which the following is a specification.

This invention relates to an improvement in the manufacture of cathodes for X-ray tubes, the object being to provide an improvement 15 construction which will increase the life of the X-ray tube by eliminating to a large extent the danger of cracking the glass at what is termed the cathode neck. In the drawings

20 Figure 1 is an X-ray tube which may be assumed to be equipped with a cathode made in accordance with our invention.

Fig. 2 is a transverse sectional view of the cathode illustrating the invention.

25 The new cathode is characterized by the fact that it is formed of two metals of different characteristics, these two metals being closely united together, or at least having a path for electrical conduction between them. *a* denotes the main body of the cathode, which may be of aluminum, the material now almost universally used for this purpose; and *b* indicates a shell of other material, such as a copper or iron, which surrounds and is either shrunk on, plated on, or pinned on to the main body, or properly secured in some other way.

30 The chief distinguishing characteristic of the two metals making up the cathode is that one should be of low atomic weight, in order that it may freely give off electrons during the operation of the tube, and the other of higher atomic weight giving off less electrons. Furthermore, the metal of the 35 higher atomic weight should preferably be adjacent to the glass wall of the tube. The cathode rather closely fills the cathode neck, and is customarily located at the point where the cathode neck is joined to the main bulb,

and the interposition of this second metal 50 of different characteristics and of greater atomic weight than the main body of the cathode eliminates unusual heating at the cathode neck, and thus reduces to a considerable extent breakage at this point. 55

The shape of the cathode may not be material, though we prefer to use a cathode like or similar to that illustrated in the patent issued to Henry Green, July 29th, 1913, No. 1,068,426.

60 We claim as our invention:

1. A cathode for use in X-ray tubes cylindrical in shape and formed from two metals 65 of different characteristics.

2. A cathode for use in X-ray tubes cylindrical in shape and formed from two metals 70 of different atomic weights.

3. A cylindrical cathode for use in X-ray tubes comprising a main body of aluminum, and a metal of higher atomic weight applied 75 and secured thereto.

4. A cylindrical cathode for use in X-ray tubes comprising a main body of aluminum, and a sleeve of metal of higher atomic 80 weight secured thereon.

5. A cylindrical cathode for use in X-ray tubes comprising a main body of aluminum, and a metal of higher atomic weight interposed between said main body and the adjacent wall of the tube and connected with 85 said main body by a path of electrical conduction.

6. The combination in X-ray tubes with the glass envelop and anode of usual construction mounted in one end of said envelop, of a cathode mounted in the other end of said envelop and operatively positioned relative thereto, said cathode comprising a cylindrical body of aluminum, and an inclosing shell formed from a metal 90 of higher atomic weight mounted thereon and connected therewith by a path of electrical conduction.

FRANCIS J. FARRELLY.
ALFRED GREINER.
